ELEMIR J. NEY, OF LOWELL, MASSACHUSETTS, ASSIGNOR TO LOWELL MANUFACTURING COMPANY.

Design No. 2,922, dated February 4, 1868.

DESIGN FOR A CARPET-PATTERN.

The Schedule referred to in these Letters Patent and making part of the same.

TO ALL WHOM IT MAY CONCERN:

Be it known that I, ELEMIR J. NEY, of Lowell, in the county of Middlesex, and State of Massachusetts, have originated and designed a new Pattern for Carpets or other fabrics, of which the following is a full, clear, and exact description, reference being had to the accompanying drawings, making part of this specification.

A, in the centre, is a set figure in the form of a diamond. Said diamond is composed of key-work, leaves, and sprigs. B is half of a set figure, and when matched will form a centre like A. C is an eight-cornered figure, the combination of which is shown in the drawing. D is half of a figure, and when matched will form a figure like C. E is an oblong-shaped figure, running at right angles to figure A. The particular form and combination are shown in the drawing.

The colors employed for the different portions of the design may be varied to suit the taste and wish of the manufacturer.

Claim.

What I claim as my invention, and desire to secure by Letters Patent, is—
